US00D656529S

(12) **United States Design Patent**
Kwon et al.

(10) **Patent No.:** US D656,529 S
(45) **Date of Patent:** ** Mar. 27, 2012

(54) **DIGITAL CAMCORDER**

(75) Inventors: **Jong-Chan Kwon**, Yongin-Si (KR);
Jun-Won Bae, Yongin-Si (KR);
Jae-Hwa Moon, Seoul (KR); **Su-Jung Ham**, Gumi-Si (KR)

(73) Assignee: **Samsung Electronics Co., Ltd.** (KR)

(**) Term: **14 Years**

(21) Appl. No.: **29/387,255**

(22) Filed: **Mar. 10, 2011**

(30) **Foreign Application Priority Data**

Dec. 17, 2010 (KR) 30-2010-0054746

(51) **LOC (9) Cl.** 16-01

(52) **U.S. Cl.** D16/202
